UNITED STATES PATENT OFFICE.

HENRY WHITE, JR., OF BUFFALO, NEW YORK.

TIE FORM.

Application filed October 11, 1921. Serial No. 507,005.

To all whom it may concern:

Be it known that I, HENRY WHITE, Jr., a citizen of the United States, residing at Buffalo, in the county of Erie and State of New York, have invented certain new and useful Improvements in a Tie Form; and I do hereby declare the following to be a full, clear, and exact description of the invention, such as will enable others skilled in the art to which it appertains to make and use the same.

The present invention relates to neckties and more particularly to four-in-hand variety and aims to facilitate the tying of the same, to maintain the knot in the required adjusted position and to prevent slipping and lastly to obviate wrinkling and insure a neat appearance.

The invention consists of a form about which the tie is shaped and a clip to secure the running end of the tie to the form whereby to hold the tie in place and maintain its set.

Other objects and advantages will be apparent and suggest themselves as the nature of the invention is understood.

While the drawing illustrates an embodiment of the invention it is to be understood that in adapting the same to meet different conditions and requirements, various changes in the form, proportion and minor details of construction may be resorted to without departing from the nature of the invention.

Referring to the accompanying drawing forming a part of the specification,

Figure 1 is a front view of the form,

Figure 2 is a side view thereof,

Figure 3 is a detail view of the clip,

Figure 4 shows the form in position after the knot has been fashioned and preliminary to passing the loose end of the tie over the form and through the knot, and

Figure 5 shows the knot completed and the running end of the tie secured by means of the clip, the loose end of the tie being turned aside.

Corresponding and like parts are referred to in the following description and designated in the several views of the drawing by like reference characters.

The form comprises a relatively slender shank 1 having a pointed end and a flattened head 2. The head 2 is laterally expanded and its corners are made rounded for engagement with the edge portions of the tie and hold the same expanded. Opposite

edges of the head 2 slope gradually and merge into the sides of the shank 1. The head 2 is deflected rearwardly as indicated most clearly in Figure 2. A catch pin 3 is attached at one end to the head 2 and extends approximately parallel with the shank 1 and is spaced therefrom. The catch pin 3 is preferably flat and its end is blunt to obviate injury to the tie since it is not required to pierce the same. Opposed depressions 4 are formed in opposite sides of the shank 1 adjacent the point thereof and are adapted to receive a clip 5 and prevent displacement thereof. A stud or projection 6 is provided in the front depression 4 and receives an eye 7 at one end of the clip 5 whereby to prevent displacement thereof. The form may be constructed of any suitable material and the catch pin 3 may constitute a part thereof or be provided in any manner.

The clip 5 is substantially of U-form and is adapted to embrace opposite sides of the shank 1 and secure the running end of the tie thereto. The clip may be constructed of any suitable material and the bill is extended beyond the shank and curves outwardly to facilitate the placing of the clip in position. The opening 7 at the outer end of one of the members is adapted to receive the stud 6 and thereby retain the clip in position.

In the application of the invention a four-in-hand tie is shaped in the usual way to provide the slip knot and preliminary to passing the loose end of the tie through the knot the form is placed in position by passing the shank 1 thereof through the knot and engaging the catch pin 3 with the cross over 8. This is indicated most clearly in Figure 4. The loose end of the tie is now passed over the head 2 of the form and through the front 9 of the knot and is drawn and shaped to present the desired appearance of a four-in-hand tie after the knot has been formed. The running end of the tie is now drawn upon to properly position the knot with reference to the collar after which the clip 5 is placed in position and secures the running end 10 of the tie to the shank 1, thereby holding the tie to adjusted position and preventing slipping or displacement thereof. This is indicated most clearly in Figure 5.

Having thus described the invention, what I claim is:—

1. A necktie form comprising a relatively slender shank pointed at one end and hav-

ing its opposite end expanded to form a head and a catch pin projecting from the head and extending substantially parallel with the shank and spaced therefrom, said shank 5 having opposed recesses adjacent the pointed end for cooperation with a clip.

2. A necktie form comprising a relatively slender shank pointed at one end and having its opposite end expanded to form a head 10 and a catch pin projecting from the head and extending substantially parallel with the shank and spaced therefrom, said shank having opposed recesses adjacent the pointed end for cooperation with a clip, one of said recesses having a stud in the bottom thereof 15 to make positive engagement with the clip to prevent displacement thereof.

3. A necktie form comprising a relatively slender shank having its lower end pointed and its upper end flared to form a head 20 which is deflected rearwardly and having its corner portions projecting outwardly in opposite directions and made rounding, and a catch pin in the rear of the shank and extending substantially parallel therewith and 25 attached at its upper end to the rear side of the said head.

In testimony whereof I affix my signature in presence of two witnesses.

HENRY WHITE, JR.
